UNITED STATES PATENT OFFICE.

JOHN H. BURKHOLDER, OF ASHLAND, OHIO, ASSIGNOR TO ELITE MANUFACTURING COMPANY, A PARTNERSHIP COMPOSED OF JOHN H. BURKHOLDER, P. E. COUNTRYMAN, AND E. L. KILHEFNER, OF ASHLAND, OHIO.

VEHICLE JACK.

Application filed June 24, 1924. Serial No. 722,014.

My invention relates to an improvement in vehicle jacks, especially jacks of the double screw type in which one lift screw telescopes within another and power is applied to one of the screws to rotate and elevate and lower the same within a hollow standard of comparatively low height. In general my object is to provide efficient means for this or any other type of screw jack whereby a lift screw will be automatically checked or stopped when elevated to its maximum and the screw will not be left in an unstable position or become disengaged from its support and collapse, and a further object is to provide a simple and effective stopping device adapted to be actuated directly by rotation of the screw without being subjected to the longitudinal pull of the screw.

In the accompanying drawings, Fig. 1 is a side elevation of a double screw jack embodying my invention, the screws being elevated and near the end of their upward travel, and Fig. 2 is a sectional view of the same parts in the same position but in a vertical plane at right angles to Fig. 1. Fig. 3 is a top view and horizontal section on line 3—3 of Fig. 1. Fig. 4 is a horizontal section of the jack on line 4—4 of Fig. 1. Fig. 5 is a perspective view of the lower end of the main lift screw. Figs. 6 and 7 are similar cross sections on line x—x of Fig. 2, Fig. 6 showing the stop member riding upon the screw thread and pressed outward, and Fig. 7 showing the stop member entered into the cam notch in the screw and in arresting engagement with the stop shoulder on the screw.

The jack illustrated in the drawings comprises a tubular standard 2 which is screw-threaded internally at its upper end to receive a main lift screw 3. A bevel gear 4 is pinned or keyed to the upper end of screw 3, and a sleeve member 5 is suspended from the upper end of screw 3 and gear 4 by a cross plate 7 which is detachably secured by screws to the arms 8—8 of the yoke-shaped upper end of sleeve 5. Gear 4 is adapted to be rotated by a bevel pinion 6 on a stub shaft 6' journaled in a lateral extension 9 of the yoke portion 10 of sleeve 5, and any suitable means may be used to rotate stub shaft 8. Rotation of gear 4 and screw 3 causes these parts to ascend or descend, and sleeve 5 is carried upwardly and downwardly with the

screw but is prevented from rotating by a pair of lugs 11 which project laterally from the upper end of standard 2 and extend into channeled guide portions 12—12 of sleeve 5. Cross plate 7 has a central opening 14 therethrough which a second and smaller screw 15 is adapted to extend, and this second screw is prevented from rotating by a projection 16 on plate 7 extending into a longitudinal groove 17 in screw 15. Main screw 3 is tubular to receive secondary screw 15, and the upper end of main screw 3 is provided with internal screw threads 18 to engage the external screw-threads on the secondary screw and thereby raise or lower the same whenever the main screw is rotated. A differential travel is thereby imparted to the two screws, and if the rotation of main screw 3 is not checked and stopped it will unscrew itself from the standard and the jack will collapse.

I therefore provide a simple and effective stopping device adapted to automatically prevent further rotation of main screw 3 when it has reached a predetermined height within standard 2. This device comprises a short bolt 20 and a spring of any suitable kind to control its action. As shown bolt 20 is affixed to the free end of a flat spring 21 mounted at one side of standard 2 beneath one of the lateral lugs 11 where the spring and bolt may have free working play within the vertical channel of guide portion 12 of sleeve 5. Bolt 20 extends through an opening in the side of standard 2 and rides constantly upon the flat top of the spiral thread 19 of main screw 3 until the lower end of the screw is raised to the top of the standard. Then bolt 20 is caused to ride inward on an eccentric portion 22 formed in the spiral thread itself until the bolt engages a squared shoulder 23 also formed in the same thread and extending into the body of the screw below the base of the thread, thereby positively stopping further rotation of the screw and preventing all possibility of unscrewing the parts accidentally. However, the bolt may be withdrawn temporarily by hand or a prying instrument to permit disassembly of the parts, but the lowering of the screw may be effected without manipulating or handling the bolt inasmuch as the reverse rotation of the screw will cause eccentric portion 22 on spiral thread 19 to

press the bolt outward where it will constantly remain as long as it rides upon the top of the screw thread. The bolt and spring are covered and protected by the channeled guide portion 12 of sleeve 5 when the sleeve is telescoped over the upper part of standard 2, and when the jack is lowered and the parts completely drawn together the sleeve rests upon the base of the standard and the two screws are telescoped within each other and the standard.

The notch which forms shoulder 23 in screw 3 extends longitudinally of the screw, preferably to the bottom of the screw, to permit axial travel of the screw while bolt 20 rides down the terminal cam portion 22 of the thread and enters the notch and engages the shoulder. Thus, the longitudinal movement and lifting power of the screw is not transmitted to the bolt, and damage and breakage are avoided.

What I claim is:

1. A vehicle jack, comprising a standard, a rotatable main screw having screw connection with said standard, a secondary lift screw mounted within said main screw, a

vertically-movable sleeve member suspended from said main screw having a channeled portion engaging said standard and adapted to prevent rotation of said secondary screw, 30 means adapted to rotate said main screw, a bolt extending through the side of said standard and a supporting leaf spring for said bolt secured to the outer side of said standard opposite said channeled portion, and a 35 stop shoulder on said main screw adapted to engage said bolt and limit the longitudinal movement of said lift screw.

2. A vehicle jack, comprising a standard, a vertically movable lift-screw mounted 40 within said standard having an operating gear fixed thereto, a vertically movable sleeve suspended from said gear having guide portions sleeved over said standard, means on said standard and lift screw adapted to limit 45 their relative movement, said sleeve normally covering said means but permitting manual release thereof when the lift screw is raised substantially to its limit.

In testimony whereof I affix my signature.

JOHN H. BURKHOLDER.
